CONDENSATION PROCESS

Vernon O. Bowles, Los Angeles, Calif., assignor to
 The Lummus Company, New York, N. Y., a
 corporation of Delaware

Application January 7, 1939, Serial No. 249,691

2 Claims. (Cl. 260—683.4)

This invention relates to the treatment of hydrocarbons, and more particularly to the condensation or alkylation of olefines with iso-paraffins in the presence of sulfuric acid, to effect a substantial conversion of said hydrocarbons into components of high anti-knock value, suitable for use as a motor fuel.

It is well known to the art that gaseous olefines may be successfully polymerized to normally liquid hydrocarbons by the action of sulfuric acid. The polymers consist of dimers, trimers, etc., a suitable fraction of which is then hydrogenated to produce the desired end product, namely iso-octanes and other paraffins of a similar boiling range, which have a high octane rating. The disadvantage of this process lies in the secondary step of hydrogenation, which involves special equipment of a high initial cost.

More recently it has been suggested that olefines and iso-paraffins can be alkylated, or condensed, in the presence of sulfuric acid, to directly yield a fraction of saturated hydrocarbons of high octane rating.

In normal present day refinery practice, there is a considerable yield of a gaseous fraction of hydrocarbons comprised substantially of those compounds containing from one to six carbon atoms per molecule, a large part of which is butenes, butane, iso-butene and iso-butane. Such gaseous products, except as fuel, are substantially valueless, although they often amount to 8% or more of the crude charge.

In accordance with my invention, I propose to utilize various constituents found in this gaseous fraction by condensing an unsaturated hydrocarbon with a saturated hydrocarbon of the iso type. I find that by suitable treatment, I can thereby obtain a liquid material which is of particular advantage as a motor fuel and which has a high octane rating. Such product commands a substantial premium as aviation gasoline, or for use as a blending agent with gasoline of lower octane rating.

More specifically, I propose to condense butene with iso-butane to produce iso-octane, but my invention is not necessarily limited to such particular compounds as it will also operate when similar compounds containing two to six carbon atoms per molecule are used, such compounds being the primary constituents of hydrocarbon overhead gases which are normally gaseous under atmospheric temperatures and pressures. My invention may also be practiced on hydrocarbons containing more than six carbon atoms per molecule if it is found desirable to operate

under suitable pressure conditions for the purpose of making a greater yield of high octane hydrocarbons and a lower yield of normal fuels.

Inasmuch as the normal gases in refinery practice are a combination of hydrocarbon compounds including but not limited to butane, butenes and iso-butane, it is the preferred practice of my invention to first absorb the butenes from a butane-butene fraction of such gases, and then remove the saturated hydrocarbons for fractionation into n-butane which is removed from the system, and iso-butane which is collected for subsequent condensation with the butenes. The butenes and iso-butane are then condensed in the presence of a suitable catalyst which may preferably be the absorbing medium containing the butenes, after which the alkylers are separated from the catalyst and are then fractionated to obtain the iso-octane.

The principal object of my invention is the production of hydrocarbons of high octane rating from a normally gaseous hydrocarbon fraction, commonly wasted in refineries, which may be obtained with considerable economy and with a substantially high yield of valuable product.

Another object of the invention is to condense an olefine obtained from a gaseous hydrocarbon fraction of refinery gases with an iso-paraffin to produce a liquid alkymer of high octane rating suitable for use as motor fuel.

Another and more specific object of the invention is to separate and remove n-butane from a mixture of butanes and butenes, thereby facilitating the subsequent condensation of the remaining iso-butane and butenes which are converted by such condensation into iso-octane.

Another object of this invention is to recover iso-butane that may be present in a spent butane-butene fraction of refinery gas after the butenes are absorbed, and to combine said iso-butane with the absorbed butenes so that substantially none of the hydrocarbons are wasted.

Further objects and advantages of the invention will appear from the following description of preferred forms of embodiment of the invention taken in connection with the attached drawings, in which:

Figure 1 illustrates a preferred flow arrangement suitable for carrying out the process; and

Figure 2 illustrates an alternative flow arrangement for carrying out the process.

In accordance with Figure 1, the butane-butene fraction of hydrocarbons from waste refinery gases enters the mixer 16 through line 10,

under sufficient pressure to be in the liquid form. In such mixer, it is preferably mixed with cold sulfuric acid to effect a substantial absorption of the butenes by said acid. This sulfuric acid may be of a concentration of from 50 to 100%, or even greater, but preferably an acid of a concentration of from 95 to 100% will be used. Said mixer may be of any suitable type to effect an intimate contact between the acid and the olefines in said hydrocarbon fraction, so that substantially all of said olefines are absorbed by the acid.

Said mixture is then conducted in line 18 to separator 20, where it separates into two liquid phases, a light hydrocarbon layer on top containing the unreacted constituents of the butane-butene fraction, and an acid oil layer on the bottom containing the absorbed olefines. Separator 20 is maintained at such a pressure that substantially all of said hydrocarbon layer flows through line 21 to fractionator 64.

The fractionator 64, which is a typical fractionating column provided with a closed steam coil 67, operates under a super-atmospheric pressure and the overhead contains the iso-butane present in the butane-butene fraction charged. This overhead flows through line 66 to condenser 68 which furnishes reflux for fractionator 64. Said reflux is returned through line 69, and the remainder of the overhead consists of the recovered iso-butane. The bottoms from said fractionator, consisting primarily of n-butane, are removed from the system in line 65.

The acid oil layer from separator 20, containing the absorbed butenes, flows through line 22 to mixer 24, where it is thoroughly agitated with the incoming iso-butane charge, also under sufficient pressure to be liquefied, from line 26. This iso-butane charge will consist of the aforesaid recovered iso-butane from line 28, together with any other available iso-butane introduced into the system. Mixer 24 may be of a type similar to mixer 16 except that it will be provided with a cooling coil 31 for controlling the temperature in this mixer.

The resulting mixture is then conducted through line 30, cooler 32, and line 34, to separator 36, in which the mixture separates into two layers, an alkymer layer on top and an acid layer on bottom. The acid layer in separator 36, which may contain a small amount of dissolved unreacted butenes, is conveniently recycled through line 38, cooler 40 and line 42 to mixer 16.

The alkymer layer from separator 36, which may contain some unreacted iso-butane and butenes, is led through line 42 to stabilizer 44 which is also a suitable type of fractionating column. The overhead, consisting substantially of said unreacted constituents, flows through line 46 to condenser 48, which furnishes reflux through line 50 to said stabilizer. The remainder of said overhead, depending upon the preponderance of butenes or iso-butane, may be recycled either to the butane-butene charge in line 10 by means of line 14, or to the iso-butane charge in line 26 by means of lines 52 and 28. Valves 49 and 51 in lines 14 and 52 control this recycling operation. A closed steam coil 45 may be provided in said stabilizer.

The bottoms from stabilizer 44 flow through line 54 to alkymer still 56, essentially a fractionating column, in which the alkymers are fractionated. The overhead, which is composed substantially of iso-octanes and compounds of a similar boiling range, flows through line 60 to con-

denser 61, part of the condensate from which is returned as reflux through line 62, the remainder being removed from the system by line 63 as the desired end product. The bottoms from said alkymer still which are heavy alkymers are removed through line 57, cooler 58 and line 59. A closed steam coil 55 may be provided to assist in the fractionation.

The acid used in absorbing the butenes in mixer 16, is also found most suitable for condensation of the butenes with the iso-butane in mixer 24, and it is preferable to use this same acid, after which the acid layer in separator 36 may be recycled to furnish the acid for absorption in mixer 16. Make-up acid may be added from time to time at 13, and spent acid may likewise be withdrawn at 39.

If it is desired to separate the iso-butane from the n-butane before absorption of the butenes, 20 the form of embodiment illustrated by Figure 2 may be used. The liquefied butane-butene charge enters fractionating tower 111, equipped with closed steam reboiling coil 112, through line 110. This tower serves the purpose of fractionally separating the iso-butane from the n-butane present in the charge; the resulting fractions each contain a portion of the olefines in the butane-butene charge.

The n-butane fraction flows through lines 113 30 and 115, and cooler 116, to mixer 117, where it is suitably admixed with cooled recycled acid entering at 118. The resulting mixture flows into separator 120 through line 119 and separates into two layers, an upper hydrocarbon layer, comprised of the n-butane in the butane-butene charge, and a lower acid-oil layer, containing the butenes. The n-butane is removed from the system at 121, while the acid-oil is sent through line 122 to mixer 133.

40 The iso-butane fraction from tower 111 is taken off overhead at 124 and is condensed in condenser 125. Condensate from condenser 125 is returned by line 126 as reflux. The remainder of said iso-butane fraction may now be treated in two different ways, namely, with recycled sulfuric acid or with acid containing absorbed butenes from separator 120. Generally, the latter method will be used, but occasionally, for purposes of controlling the amount of iso-butane supplied to the condensation reaction, it may be desirable to employ the former method of treatment.

When the first method is used, the remainder of the iso-butane fraction flows through line 127 to mixer 128 to be admixed with recycled sulfuric acid from line 129, which absorbs the butenes present in said iso-butane fraction. The mixture of acid and hydrocarbons then enters separator 131 through line 130, separating into an upper layer composed substantially of iso-butane and a lower acid layer containing the absorbed butenes. This lower layer is removed in line 136 to be combined with the acid-oil layer from separator 120 before entering mixer 133. The upper iso-butane layer leaves the separator 131 in line 132, for use in the condensation reaction in mixer 133. Any excess iso-butane may be bled from the system at 155.

When the latter method is used, the remainder of the iso-butane fraction flows directly to mixer 133 through lines 138 and 139. Additional iso-butane, as needed, may be introduced into the system at 137.

Condensation of the butenes with the iso-butane takes place in mixer 133, which is equipped with a cooling coil 134. The mixture of alky-

mers, unreacted constituents, and acid, flows through cooler 140 in line 141 to separator 142, in which the alkymers separate out from the acid.

The acid layer in separator 142 is removed through cooler 143 and recycled in line 144 for further use in the absorption of butenes. Spent acid may be removed at 157, and make-up acid may be added, as necessary, at 156.

The alkymers which separate out in 142, flow in line 145 to stabilizer 146, where any unreacted constituents are removed by stripping. The overhead, consisting of said unreacted hydrocarbons, flows through line 149 to condenser 158, the condensate from which is returned as reflux at 151. The remainder of the overhead is recycled for recovery of said hydrocarbons to mixer 133 in line 138. Stabilized alkymers are removed at 148 for further treatment in the alkymer still. Stabilizer 146 may be equipped with steam coil 147.

It may be found desirable to operate tower 111 in such a way as to have the majority of the butenes go off overhead in the iso-butane fraction. If such operation is found desirable, and the amount of butenes in the n-butane fraction is negligible, an alternative method of treatment may be used. The n-butane fraction may be removed directly from the system in lines 113 and 114, while the iso-butane fraction, containing substantially all the butenes, flows through lines 124, 139 and 138 directly to mixer 133, where condensation of the butene with the iso-butane is effected. Acid is recycled from separator 142 through lines 144, 129, 158 and 122 to mixer 133. Recycling of the overhead from stabilizer 146 is not affected by this procedure.

Olefines that may be used in this process consist of ethylene, propylene, 1-butene, 2-butene, iso-butene (iso-butylene), di-isobutylene, tri-isobutylene, 1-pentene, 2-pentene, tri-methyl-ethylene, iso-pentene, and the like, or of combinations of said olefines or of a fraction of hydrocarbons containing one or more of said olefines. Iso-paraffins which may be used consist of iso-butane, iso-pentane, iso-hexane and the like.

Although improvements have been described with a butane-butene fraction of hydrocarbons and iso-butane, these are not limited to reactions between olefines and iso-paraffins having the same number of carbon atoms; for example, this process may be used to bring about the condensation of propylene with iso-pentane or any other iso-paraffin, or of butenes with iso-pentane or any other iso-paraffin, or of ethylene with an iso-hexane, or any other iso-paraffin.

The source of hydrocarbons for this reaction is not necessarily limited to waste refinery gases. Any source furnishing these hydrocarbons in suit-

able quantities may be utilized, to convert the hydrocarbons into iso-octane and the like.

The process as a whole provides a method of economically and readily converting low boiling point hydrocarbons into a substantial yield of high grade gasoline with a high octane rating. In addition, it furnishes a means to utilize iso-butane, which at the present has little more value than as a low grade gaseous fuel. Recovery and recycling of any iso-butane present in the initial charge, and recycling of the overhead from the alkymer stabilizer, make possible practically full utilization of all the useful hydrocarbons introduced into the system, and thereby result in an increased yield of high-octane hydrocarbons.

While I have described several forms of embodiment of my invention, it will be understood that I do not wish to be limited to them and that other modifications may be made thereto, and that I therefore desire a broad interpretation of my invention within the scope and spirit of the description and the claims appended hereinafter.

I claim:

1. A process for alkylating butenes with iso-butane to form a high octane motor fuel, which comprises the steps of fractionating a butane-butene fraction of hydrocarbons into iso-butane and n-butane fractions, each of which contains a part of said butenes, treating each of said fractions separately with concentrated sulfuric acid to absorb the butenes therein, separating the acid-butene mixtures from the unabsorbed hydrocarbons, combining said mixtures, reacting the combined acid mixtures with iso-butane in the presence of the concentrated acid under alkylating conditions, separating the alkymers product from the acid, and fractionating such product to obtain the desired end product.

2. A process for alkylating butenes with iso-butane to form a high octane motor fuel, which comprises the steps of fractionating a butane-butene fraction of hydrocarbons into iso-butane and n-butane fractions, each of which contains a part of said butenes, treating the n-butane fraction with concentrated sulfuric acid to absorb the butenes therein, separating the resulting acid-butene mixture from the unabsorbed hydrocarbons, adding further iso-butane to said iso-butane fraction, treating the iso-butane fraction with said acid mixture to absorb the butenes present in this fraction and to alkylate the absorbed butenes with the iso-butane in the presence of the concentrated acid, separating the alkymers product from the acid, and fractionating said alkymers product to obtain the desired end product.

VERNON O. BOWLES.
